UNITED STATES PATENT OFFICE.

HANS H. WANDERS, OF BOSTON, MASSACHUSETTS, ASSIGNOR TO NORTHERN INDUSTRIAL CHEMICAL COMPANY, OF BOSTON, MASSACHUSETTS, A CORPORATION OF MASSACHUSETTS.

TIMER.

Application filed May 9, 1921. Serial No. 468,159.

This invention relates to timers for gas engines, and has been more particularly designed with reference to the particular conditions arising in connection with Ford 8 cars.

This invention comprises an insulating casing or head, to which the usual timing control is connected through a crank arm fixed thereto, and means by which this arm 10 is secured without danger of metal parts projecting through the casing which might be liable to cause short circuits.

A further feature relates to the manner of mounting the movable contact shoe actuated by the timing shaft so that end play 13 of the shaft has no harmful effect.

Still another feature relates to the construction of the contact shoe and its mounting whereby proper contact with the casing 20 terminals is ensured.

For a more complete understanding of this invention, together with further objects, advantageous details and combinations of parts, reference may be had to the accompanying drawings illustrating certain embodiments thereof, in which

Figure 1 is an outer end elevation of the timer casing.

Figure 2 is a cross section on line 2—2 20 of Figure 1.

Figure 3 is a cross section on line 3—3 of Figure 1, the timer shaft and contact shoe being shown in dotted lines to indicate their relative positions.

Figure 4 is an inner end elevation of the casing, the actuating arm being removed and the contact shoe and its path of movement being indicated thereon.

Figure 5 is an end view of the contact shoe and its sleeve mounting on the timer shaft.

Figure 6 is a side elevation of the same.

Figure 7 is an end view from the opposite direction to Figure 5.

Figure 8 is a section on line 8—8 of Figure 5.

Figure 9 is an end elevation of a shoe and its carrier plate or vane, showing a modified construction.

Figures 10 and 11 are sections on lines 10—10 and 11—11 respectively of Figure 9.

Referring more particularly to Figures 1 to 4, at 1 is indicated a cap composed of insulating material such as bakelite. This cap or casing has an outwardly extending sleeve portion 2 having a dished end 3 for the reception of the usual cap retaining means found in Ford cars. The sleeve 2 merges into a circular disc portion 4 having a marginal laterally extending flange 5. In order to determine the timing, the member 1 is mounted so as to be rocked slightly in the usual manner. For the purpose of rocking this cap a crank arm 6 having a laterally extending portion 7 for engagement with the timer control rod is provided. This arm 6 is fixed to the casing 1 by means of rivets, as shown at 8, each rivet comprising an enlarged base portion 9 which is molded in the casing. The outer end of 70 each rivet is hollow to form a thin circular wall 10, which may be inserted in a suitable perforation in the arm 6 and bent over the outer face of the arm to hold it securely in position. As shown in Figure 2, this arm is fixed in position within a slot 11 in a lug 12 extending outwardly from the face of the disc portion 4.

The cap 1 carries contacts leading to the engine cylinders, each contact comprising a button 15 having a knurled outer face so that it may be retained projecting through the disc portion 4, by molding it therein. The inner face 16 of each button is flush with the inner face of the disc portion 4, and 85 projecting from its opposite face is a threaded portion 17, on which may be screwed the binding nut 18 for attaching the wire leading to the spark plug of the respective cylinder. Adjacent each button words to indicate the wire connections to the proper spark plugs are preferably molded in the casing, (see Figure 1.)

Contact is made with the buttons serially by means of a suitable contact shoe, which is carried by the usual timing shaft, indicated in dotted lines at 20 in Figure 3. This timing shaft as it rotates is found to

have a certain amount of end play, and in order to provide for proper contact at all times the shoe is mounted on the shaft in the following manner. Referring to Figures 3, 5, 6 and 7, at 21 is shown a sleeve fitting over the end of the shaft 20 and having near one end thereof a slot 22 engageable with a key or pin 23 fixed to the shaft. By this means the sleeve is prevented from 10 rotation relative to the shaft. The other end of this sleeve is provided with a pair of laterally projecting ears 24 having a pair of aligned perforations therein for the reception of a pintle pin 25. Outwardly of the 15 lugs 24, the forked ends of a thin vane or plate 26 are journaled on the pintle pin 25, this vane or plate carrying the contact shoe, as will be described. Surrounding the pintle pin 25 between the lugs 24 are a 20 pair of coil springs 27, one end of each spring bearing against one face of the vane 26 at 28, and the other end at 29 being passed through a perforation 30 in a lug 31 extending outwardly from the sleeve 21 25 and positioned centrally adjacent the ends of the lugs 24. These springs serve to urge the plate into the position shown in Figure 6 so that the shoe 32 carried thereby may be pressed into contact with the inner face 30 of the disc portion 4 of the casing to contact serially with the buttons 15.

In order to retain the shoe 32, the plate 26 is perforated at 33 to allow the shoe 32 to pass freely therein. One end of this shoe 35 has a laterally extending flange 34, forming a head sufficiently long to extend or bridge over the ends of the perforation 33 so that the shoe may not pass entirely therethrough. In order to retain the shoe 32 40 in position in the perforation, the plate 26 has cut and struck up or offset therefrom a retaining flange or arm 35, which has a small tit 36 formed thereon and projecting toward the flanged end of the shoe 32. These 45 parts are so proportioned as to allow considerable loose play of the shoe 32 so that it may properly engage the disc portion 4 and allow it limited universal movement relative to the plate 26.

50 In operation, the inner face of the shoe bears against the inner face of the disc portion 4 or the flush ends 16 of the buttons 15, the shoe being pressed backwardly against the tit which forms a substantially point contact therewith. Moving of the shoe by the rotation of the shaft 20 presses the shoe against the edge of the perforation in the plate, which thus gives a substantial line contact therewith, this contact being sufficiently narrow to effectually squeeze out any dirt which might get in between the shoe and the plate, so that a good contact is always ensured.

55 In Figures 9 to 11, a slightly modified 60 mounting of the shoe is shown, in which the carrying plate 26' is formed with downwardly extended flange portions 40 shaped substantially as the surface of a sphere to form a substantial ball contact with the curved outer faces 41 of the shoe 32'. This 70 construction allows the universal movement of the shoe without substantial loose play, but the construction first described is believed preferable because of the line contact between the shoe and the holding plate, 75 which ensures a good electrical contact. In this modified construction also, a retaining arm or flange 35' struck from the material of the plate 26' and having a tit 36' thereon is employed to hold the shoe in position in the plate 26'.

Having thus described certain embodiments of this invention, it should be evident to those skilled in the art that many changes and modifications might be made therein 80 without departing from its spirit or scope as defined by the appended claims.

I claim:

1. An electrical contact element comprising a shoe, a thin plate having a perforation to receive said shoe, and means for retaining said shoe loosely in said perforation to contact with the edge of said plate within said perforation. 90
2. An electrical contact element comprising an unattached shoe, a plate having a perforation to receive said shoe loosely, and a retaining flange cut and bent from said plate and extending over one face of said shoe. 95
3. An electrical contact element comprising an unattached shoe having a laterally extending flange at one end thereof, a plate having a perforation to receive said shoe, the flange thereon bridging said perforation, and a flange cut and bent from said plate extending over the flanged end of said shoe to retain said shoe loosely in position. 100
4. An electrical contact element comprising an unattached shoe having a laterally extending flange at one end thereof, a plate having a perforation to receive said shoe, the flange thereon bridging said perforation, and a flange on said plate extending over and spaced from the flanged end of 110 said shoe to retain said shoe loosely in position.
5. An electrical contact element comprising an unattached shoe having a laterally extending flange at one end thereof, a plate having a perforation for loosely receiving said shoe, the flange thereon bridging said perforation, a flange cut and bent from said plate and projecting over the flanged end of said shoe, and a tit on said flange against 120 which said shoe may contact.
6. In a timer, a rotary timing shaft, a thin plate carried by said shaft and having an opening therethrough and an offset flange projecting partly over said opening, 125 130

and a headed contact member loosely seated in said opening, the flange overlying the said opening, and a headed contact member 10 loosely seated in said opening, the flange overlying the head thereof and said head bridging said opening.

8. 7. In a timer, a rotary timing shaft, a thin plate carried by said shaft and having an opening therethrough and an offset flange projecting partly over said opening.

In testimony whereof I have affixed my signature.

HANS H. WANDERS.
